(57) **CLAIM**

The ornamental design for a pet water fountain, as shown and described.

DESCRIPTION

FIG. 1 is a front, top perspective view of a pet water fountain, showing the new design.

FIG. 2 is top plan view thereof.

FIG. 3 is a left side elevation view thereof, the right side elevation view being a mirror image.

FIG. 4 is a bottom plan view thereof.

FIG. 5 is a rear elevation view thereof; and,

FIG. 6 is a front elevation view thereof.

The broken lines in the drawings depict portions of the pet water fountain that form no part of the claimed design.

1 Claim, 6 Drawing Sheets
